UNITED STATES PATENT OFFICE.

CECIL F. DAWSON, OF EASTON, PENNSYLVANIA, ASSIGNOR TO INDIVIDUAL DRINKING CUP COMPANY, INC., OF EASTON, PENNSYLVANIA, A CORPORATION OF PENNSYLVANIA.

METHOD AND APPARATUS FOR SECURING CLOSURE CAPS TO PAPER RECEPTACLES.

Application filed December 11, 1923. Serial No. 680,035.

This invention relates to an improved method and apparatus for securing closure caps to paper receptacles and while susceptible of a wide range of usefulness in providing closed paper containers or packages for various purposes, it is especially applicable to paper cups that are used for serving ice cream and drinks for providing temporary covers or closures for said cups when the ice cream or drinks are to be carried from the soda fountain to the consumer.

The object of the invention is to provide a simple method and apparatus whereby closure caps can be quickly inserted within paper receptacles of tapering form to effect an efficient interlocking engagement of the same therewith without the necessity of preliminary or separately preparing a groove or seat in the receptacle to receive the marginal portion of the cap, and without fracturing or damaging the receptacle so that it is possible to employ paper drinking cups or other containers in the usual form free from a groove at the upper end thereof when not requiring a cover, and to readily convert the cup into a closed package of inexpensive construction, when desired.

In accordance with my improved method a paper cup or other container of tapering form is supported exteriorly and held confined inwardly of its larger end portion against distortion, and while so supported and held, a closure cap consisting of a stiff paper disk of the proper size to correspond with the size of the larger end of the paper container is forced uniformly or evenly into the outer end of the receptacle with sufficient pressure and to a sufficient distance to stretch and bend outwardly the side wall of the receptacle to effect a secure interlocking connection between the parts, the wall of the receptacle above the point of support being given a slight outward bulge by the insertion of the cap, and a groove or seat formed at the interior of the receptacle in which the marginal portion of the closure cap is firmly seated.

For practicing the improved method, the invention comprehends a tubular or chambered holder or support adapted to encompass the major portion of the receptacle be-

low the larger end portion thereof in which the closure cap is to be inserted, said tubular or chambered holder being of a size and shape corresponding to that of the major portion of the receptacle to closely fit about and support the same against distortion. The invention also contemplates in combination with the holder for the receptacle, a presser member or plunger provided with means for holding a closure cap thereon and adapted to force the closure cap evenly into the end portion of the receptacle while the latter is supported in the holder, together with means for regulating the distance the closure cap is forced into the receptacle and the pressure exerted upon the side wall thereof.

The invention, with other objects and advantages thereof, will be understood from the hereinafter contained detail description, when considered in connection with the accompanying drawings, forming part hereof, and illustrating apparatus for carrying out the method.

In the drawings:

Figure 1 is a side elevation of a paper cup seated in the holder prior to the insertion of a closure cap therein, the holder being shown in section, and the presser member with a closure thereon being shown in side elevation above the upper end portion of the cup in centered relation therewith.

Figure 2 is a similar view, without the presser member, after the closure cap has been forced into the cup into interlocking engagement therewith.

Figure 3 is a detail inverted top plan view of the presser member or plunger.

Figure 4 is a detail top plan view of a closure cap.

Figure 5 is a detail section of the plunger or presser member with a portion of the suction pipe connection connected therewith.

Figure 6 is a detail section, on an enlarged scale, of an upper portion of the cup and closure cap after the closure cap has been inserted within the receptacle.

Figure 7 is a detail view of the valve for the suction holding means.

Figure 8 is a horizontal section on the line 8—8 of Figure 5.

Referring particularly to Figure 1 of the drawings, *a* designates a paper receptacle of tapering form, the particular receptacle illustrated, by way of example, being one of the well known constructions of paper drinking cups commonly employed for serving drinks at soda fountains, the same being of trunco-conical shape and having a bottom *a'*, a side wall *a²*, and an outwardly curled or rolled top flange *a³*. *b* designates a closure cap consisting of a paper disk of the required strength and stiffness. The cap *b* is preferably, as shown, of a diameter slightly less than that of the upper end of the receptacle *a* so that the same can readily enter within the upper end of the receptacle.

The tubular or chambered support or holder for the receptacle, in this instance, is shown as a metal casing or shell *c* of a shape and size corresponding to that of the paper cup or other container *a* to closely surround the major portion of the receptacle below the point to which the closure cap is to be inserted into the larger upper end portion of the receptacle, the casing or shell *c* extending over the upper part of the receptacle a sufficient distance to afford the necessary support for the receptacle adjacent the point of insertion of the closure cap while at the same time permitting of the necessary stretching or bending outwardly of said upper portion of said receptacle to form a seat or groove therein for the marginal portion of the closure cap.

d designates a plunger or presser member in the form of a plug or block having a lower trunco-conical reduced part *d'* and an upper adjoining cylindrical enlarged part *d²*. The bottom face of the lower part *d'* of the plunger or presser member is of substantially the same diameter as that of the closure disk *b* and is adapted to enter the receptacle. The plunger *d* is provided with suction means for holding a cap thereon, said means including a passage leading through the plunger to the bottom face thereof together with suction means connected with said passage. The plunger *d* is shown provided with an interior chamber *d⁴*, openings *d⁵* leading therefrom to its bottom face, and a passage *d⁶* leading through the same from its upper face to said chamber *d⁴*. *e* designates a flexible hose connection leading from the upper end of the passage *d⁴* to any suitable form of vacuum creating means (not shown). *d⁷* designates a short tubular hand grip part having a detachable threaded connection with a collar *e'* on the nipple *e²* which engages a threaded opening in the upper part of the plunger (see Figure 5 of the drawings). The enlarged upper part *d²* of the presser member is of a diameter greater than that of the larger end of the receptacle *a*, and is adapted at its lower face *d⁸* to engage the outer

end or top flange *a³* of the receptacle, said enlarged upper part *d²* serving as a stop to limit the distance the lower part *d'* of the presser member can force the closure cap into the receptacle and the degree of pressure to which the side wall of the receptacle is subjected, the cap being inserted into the receptacle a predetermined distance nicely gaged in accordance with the size of the closure disk relative to the larger end of the receptacle, and the character of material used, etc., to produce the desired interlocking of the parts without fracturing or crushing the receptacle.

In carrying out the method the receptacle *a* is positioned within the holder *c*. A closure cap *b* is supplied to the bottom face of the plunger or presser member *d*, and the closure cap *b* held on the plunger or presser member in properly centered relation thereto is then forced inwardly into engagement with the side wall of the receptacle by the plunger or presser member, the latter being adapted to be operated by hand, by pressing or tapping thereon. After the closure cap has been forced into engagement with the side wall of the receptacle, upon withdrawal of the plunger or presser member, the hold exerted by the suction means upon the closure cap is broken, the closure cap being left seated in place in secure interlocking relation with the receptacle, the frictional engagement between the closure cap and the side wall of the receptacle being such as to overcome the holding force exerted by the suction means which is, as will be readily understood, relatively slight, just sufficient to hold the relatively light closure cap upon the bottom face of the plunger. If desired, a valve *e³* interposed in the flexible pipe connection *e*, may be employed, said valve being adapted to cut off communication with the suction means and establish communication between the suction chamber of the plunger and the atmosphere to relieve the suction on the cap after the same has been forced into interlocking engagement with the receptacle.

My improved method and apparatus, as hereinbefore set forth, provides for quickly and easily securing closure caps to paper receptacles of tapering form. It will be noted that by providing for carrying the closure cap by the plunger, the cap is definitely located in centered relation with the open end of the receptacle in the application of the closure cap thereto. The preliminary or separate grooving or shaping of the receptacle to provide a bulged seat portion to receive and interlock with the marginal portion of the cap is entirely avoided, the invention making it possible to use drinking cups or containers in the usual continuous smooth form or free from a groove at the upper mouth portion thereof, and to readily con-

vert such cups into closed packages or containers, as desired, the packages so formed being of an inexpensive nature.

It will be understood that the invention is applicable to secure closure caps to various kinds of paper receptacles other than that of the particular form of drinking cup shown in the drawings, and that the apparatus shown may be accordingly modified and changes made therein, as will appeal to those skilled in the art and falling within the scope of the appended claims without departing from the spirit of the invention.

What I claim is:

1. The improved method of securing closure caps to paper receptacles of tapering form which consists in forcing a closure cap in flat form within the larger end portion of the tapering receptacle to stretch and bend outwardly the side wall of the receptacle to form a seat therein and effect an interlocking engagement of the closure cap therewith while supporting the side wall of the receptacle below the point of insertion of the closure cap against distortion.

2. The improved method of securing closure caps to paper receptacles of tapering form which consists in forcing a closure cap of flat form within the larger end portion of the tapering receptacle by pressure applied uniformly throughout the closure cap to stretch and bend outwardly the side wall of the receptacle to form a seat therein and effect an interlocking engagement of the closure cap therewith while holding confined against distortion the side wall of the receptacle below and adjacent to the point of insertion of the closure cap.

3. An apparatus for securing closure caps to paper receptacles of tapering form, said apparatus comprising means to confine the side wall of the receptacle inwardly of the larger end thereof against lateral distortion in combination with a presser member in the form of a block adapted to be pressed by the hand to force a closure cap evenly into the larger end of the receptacle in tight fitting engagement therewith, said presser member having a tubular handle part disposed centrally of its upper side, and said presser member having a passage extending from its upper side to the bottom face thereof, and a flexible hose connection secured to the presser member at its upper side centrally thereof to communicate with said passage, said hose connection extending through the tubular handle part and being adapted to be connected to suction creating means.

4. An apparatus for securing closure caps to paper receptacles of tapering form, said apparatus including means to confine the receptacle inwardly of the larger end thereof against lateral distortion in combination with a presser device in the form of a block

adapted to be pressed by the hand to force a closure cap evenly into the larger end of the receptacle in tight fitting engagement therewith, said block having a centrally disposed lower portion provided with an end face of the same shape and diameter as that of the closure cap to engage the face of the cap and adapted to enter the end portion of the receptacle, and the block having an upper annular portion projecting a substantial distance outwardly beyond said lower portion forming an extended bearing portion for the hand of the operator for applying pressure to the block, and said annular portion also being adapted to engage the outer end of the receptacle and serve as a stop to limit the distance the lower portion of the block enters the receptacle.

5. The improved method of securing closure caps to paper receptacles of tapering form which consists in supporting the side wall of the receptacle below the point of insertion of the cap against distortion, and while so supporting the receptacle forcing a closure cap of flat form within the larger end portion thereof by means of a plunger upon which the closure cap is held flat thereto against to stretch and bend outwardly the side wall of the receptacle to form a seat therein and effect an interlocking engagement of the closure cap therewith.

6. An apparatus for securing closure caps to paper receptacles of tapering form, said apparatus comprising means to confine the side wall of the receptacle inwardly of the larger end thereof against lateral distortion in combination with a presser member in the form of a block adapted to be pressed by the hand to force a closure cap evenly into the larger end of the receptacle in tight fitting engagement therewith, said presser member having a passage extending from its upper side to the bottom face thereof, and a flexible hose connection secured to the presser member at its upper side and leading to said passage, said hose connection being adapted to be connected with suction creating means.

7. An apparatus for securing closure caps to paper receptacles of tapering form, said apparatus including means to confine the receptacle inwardly of the larger end thereof against lateral distortion in combination with a presser device in the form of a block adapted to be pressed by the hand to force a closure cap evenly into the larger end of the receptacle in tight fitting engagement therewith, said block having a centrally disposed lower portion provided with an end face of the same shape and diameter as that of the closure cap to engage the face of the cap and adapted to enter the end portion of the receptacle, and the block having an upper annular portion projecting a substantial distance outwardly beyond said lower portion.

portion forming an extended bearing portion for the hand of the operator for applying pressure to the block, and said annular portion also being adapted to engage the outer end of the receptacle and serve as a

presser device having means for holding a closure cap on the lower face of the lower portion thereof.

10

In testimony whereof I hereunto affix my signature.

CECIL F. DAWSON.
